UNITED STATES PATENT OFFICE.

HARVEY P. ALTMAN, OF FINDLAY, OHIO.

AUXILIARY SPARK-GAP.

1,346,522.

Specification of Letters Patent. Patented July 13, 1920.

Application filed March 30, 1918. Serial No. 225,814.

To all whom it may concern:

Be it known that I, HARVEY P. ALTMAN, a citizen of the United States, residing at Findlay, in the county of Hancock and State 5 of Ohio, have invented certain new and useful Improvements in Auxiliary Spark-Gaps; and I do hereby declare the following to be a full, clear, and exact description of the invention, such as will enable others skilled in 10 the art to which it appertains to make and use the same.

This invention relates to improvements in auxiliary spark gaps and has for one of its objects the provision of a device of this character, which can be readily interposed between the feed wire and the spark plug of an engine so that it can be determined if the 15 spark plug is firing.

Another object of this invention is the provision of means whereby the auxiliary spark created by the auxiliary spark gap can be adjusted as desired.

A still further object of this invention is the provision of an auxiliary spark gap of 25 the above stated character, which shall be simple, durable and efficient, and which may be manufactured and sold at a comparatively low cost.

With these and other objects in view as 30 will become more apparent as the description proceeds, the invention consists in certain novel features of construction, combination and arrangement of parts as will be hereinafter more fully described and 35 claimed.

For a complete understanding of my invention, reference is to be had to the following description and accompanying drawing, in which:—

40 Figure 1 is a side elevation of an auxiliary spark gap constructed in accordance with my invention,

Fig. 2 is a vertical sectional view of the same,

45 Fig. 3 is a top plan view of the same.

Referring in detail to the drawing, the numeral 1' indicates a fragmentary portion of an engine having the usual spark plug 2', and to which my invention is adapted to be 50 applied. A base 1 has secured to one end thereof, a plate 2 which projects beyond the

end of the base and is bifurcated to form resilient gripping arms 3 adapted to engage the central electrode 4 of the spark plug 2. The other end of the plate 2 is disposed at 55 right angles to form an auxiliary stationary electrode 5. The base 1 is constructed of any desirable insulating material. A member 6 is provided with a horizontal internally threaded opening and with a screw threaded 60 shank 7 upon one end which extends through an opening in one end of the base 1 and on which is threaded a clamping nut 8 for the purpose of securing an electrical feed wire 10 thereto. An auxiliary adjustable electrode 11 is threaded in the member and has secured to its outer end a finger grip 12 and also has threaded thereon a lock nut 13.

In operation, the arms 3 are applied to the central electrode 4 of the spark plug and the 70 electrical feed wire 10 is connected to the threaded shank 7. The lock nut 13 is then released from engagement with the member 6 and the movable auxiliary electrode 11 is moved toward and from the stationary electrode 5 until the correct spark is obtained between the movable electrode 11 and the stationary electrode 5.

From the foregoing description taken in connection with the accompanying drawing, 80 it will be noted that a device has been provided wherein the electrical feed wire can be readily and conveniently attached to the central electrode of the spark plug and whereby means is provided to determine if 85 the electrical current is flowing through the feed wire to the spark plug as the spark will be visible at all times between the movable electrode 11 and the stationary electrode 5.

While I have shown and described the preferred embodiment of my invention, it will be understood that minor changes in construction, combination, and arrangement of parts may be made without departing 95 from the spirit and scope of the invention as claimed.

What I claim as new is:—

A spark plug gap comprising an insulated base, a plate secured to one end of the base 100 and having one end projecting beyond said base and bifurcated to form a pair of spaced

resilient gripping arms adapted to engage the electrode of a spark plug, said plate having its other end disposed at right angles to form an auxiliary stationary electrode, a member having a threaded shank extending through the base and receiving a nut for securing an electrical feed wire thereto, a threaded auxiliary movable electrode adjustably carried by the member, and a nut

threaded on the movable electrode for locking the same in adjusted positions.

In testimony whereof I affix my signature in presence of two witnesses.

HARVEY P. ALTMAN.
